UNITED STATES PATENT OFFICE
2,566,473
SNOW MELTING APPARATUS
Benjamin S. Wilson, Akron, Ohio
Application February 6, 1950, Serial No. 142,662

1. Claim. (Cl. 126—271.2)

This invention relates to new and useful improvements and structural refinements in apparatus for removing snow, and the principal object of the invention is to facilitate convenient and expeditious removal of snow by the process of melting.

In particular, the invention concerns itself with the provision of snow melting means carried by a vehicle such as a truck, a locomotive, or the like, an important feature of the invention residing in the provision of a flame throwing unit mounted at the front of the vehicle, together with means carried by the vehicle for delivering fuel under pressure to the flame throwing unit.

Another feature of the invention resides in the provision of means for raising and lowering the flame throwing unit relative to the ground, while a still further feature lies in the structural arrangement of the flame throwing unit per se, this including means for pre-heating a conduit carrying fuel to flame throwing nozzles, whereby substantial operating efficiency and snow melting ability are achieved.

Some of the advantages of the invention reside in its simplicity of construction, in its efficient operation as aforesaid, and in its adaptability for use in association with vehicles of different types.

With the above more important objects and features in view and such other objects and features as may become apparent as this specification proceeds, the invention consists essentially of the arrangement and construction of parts as illustrated in the accompanying drawings, in which:

Figure 1 is a top plan view of the invention installed on a vehicle, for example, a truck;

Figure 2 is a side elevational view of the device shown in Figure 1;

Figure 3 is a fragmentary sectional detail, taken substantially in the plane of the line 3—3 in Figure 1;

Figure 4 is a longitudinal sectional view of the flame throwing unit, this view being taken substantially in the plane of the line 4—4 in Figure 3, and

Figure 5 is a longitudinal sectional view of the flame throwing unit, taken substantially in the plane of the line 5—5 in Figure 4.

Like characters of reference are employed to designate like parts in the specification and throughout the several views.

Referring now to the accompanying drawings in detail, the general reference character 10 designates a conventional vehicle, such as for

example, a truck, or the like, the same having a platform 12 on which is mounted a fuel tank 14 having an outlet pipe 16 connected to a suitable pump 18 driven by a motor 20. The latter as well as the pump 18 may be mounted on the platform 12 together with the tank 14, and the outlet pipe 16 may be provided with a shut-off valve 22 for obvious reasons. The outlet of the pump 18, in turn, is connected by a pipe 24 to a manifold 26 having a plurality of shut-off valves 28, 30, 32 and 34 thereon, and flexible fuel hoses or lines 36, 38, 30 and 42 are connected to the respective shut-off valves, as is clearly shown in Figure 1.

It is to be noted that a by-pass 44 extends from the pipe 24 to the tank 14 and is equipped with a control valve 46, so that the pump 18 may feed back to the tank 14 in the event the valves 28—34 inclusive are partly or fully closed. In addition, a shut-off valve 48 may be provided on the pipe 24 if so desired.

The several fuel lines or hoses 36—42 inclusive are connected to a flame throwing unit which is designated generally by the reference character 50 and is mounted at the front end of the vehicle 10, such as for example, on the usual front bumper bar 52. This may be achieved by securing to the bumper bar a pair of longitudinally spaced clamps 54 which have pivotally connected thereto as at 56 a pair of upwardly and downwardly swingable members 58 clamped on a horizontally elongated, substantially cylindrical jacket 60 constituting a component of the flame throwing unit 50.

Upward extensions 62 are rigidly secured to the brackets 54 (see Figure 3) and provide bearings for a transverse shaft 64 carrying a pair of cranks 66 which, in turn, are pivotally connected by links 68 to the members 58. An additional crank 70 is secured to the shaft 64 and is operatively connected by a rod 72 to a control lever 74 in the "cab" of the vehicle 10, it being apparent from the foregoing that by simply manipulating this lever, the entire flame throwing unit 50 may be raised or lowered with respect to the ground.

The aforementioned jacket 60 of the unit 50 is provided at the opposite ends thereof with a pair of caps 76 and a tubular fuel conduit 78 is supported by these caps and extends longitudinally in the jacket 60 but is spaced therefrom so as to afford what may be referred to as an annular pre-heating chamber 80. The end portions of the conduit 78 project outwardly from the caps 76 and are provided with suitable nip-

ples 82 for connection to the aforementioned fuel hoses 36, 42, whereby fuel may be delivered from the tank 14 under pressure of the pump 18 into the conduit 78. A row of longitudinally spaced flame throwing nozzles 84 are provided on and communicate with the interior of the conduit 78, it being noted that the nozzles radiate outwardly from the conduit in the chamber 80 and project outwardly from the jacket 60, substantially as shown. It will also be noted that by simply manipulating the control lever 14, the entire unit 50 may be lowered or raised so as to properly direct the flame throwing nozzles 84 on the snow which is to be melted.

In order to assure the utmost operating efficiency of the flame throwing and snow melting operation, a pair of pre-heating nozzles 86 are provided in the opposite end portions of the chamber 80, these pre-heating nozzles being equipped with suitable nipples 88 which extend outwardly from the respective caps 76 for connection to the fuel hoses 38, 40. By virtue of the pre-heating nozzles 86 the temperature in the chamber 80 will be substantially raised and the fuel in the conduit 78 will become considerably heated in readiness for efficient subsequent flame throwing operation from the nozzles 84.

A plurality of air apertures or openings 90 are provided in the opposite end portions of the jacket 60 so as to facilitate admittance of air to support combustion at the nozzles 86 and also, so as to facilitate a discharge of products of combustion from the chamber 80.

If desired two auxiliary flame throwing units 92 may be installed at opposite sides of the vehicle forwardly of the rear wheels 94, so as to fully melt any snow or ice such as may remain on the ground after the unit 50 passes thereover and thereby assure proper traction of the rear wheels.

Each of the auxiliary units 92 consists of a flame throwing nozzle 96 adjustably connected by a swivel joint 98 to a sleeve 100, the latter being positioned upon a horizontal rod 102 carried by a bracket 104 secured to the vehicle frame. The two nozzles 96 receive their fuel supply through the medium of flexible hoses 106, 108 which are joined together and are connected to a valve 110 on the manifold 26. Oscillation of the nozzles 96 may be effected by a transverse

control shaft 112 connected to the joints 98 of the two units, which shaft, in turn, is operatively connected by a rod 114 to a second control lever 116 in the cab of the vehicle.

It is believed that the advantages and use of the invention will be readily apparent from the foregoing disclosure and accordingly, further description thereof at this point is deemed unnecessary.

While in the foregoing there has been shown and described the preferred embodiment of this invention it is to be understood that minor changes in the details of construction, combination and arrangement of parts may be resorted to without departing from the spirit and scope of the invention as claimed.

Having described the invention, what is claimed as new is:

In a flame throwing unit for snow melting apparatus, the combination of a horizontally elongated jacket provided in end portions thereof with air openings, a pair of caps at the opposite ends of said jacket, a fuel conduit supported by said caps and extending longitudinally in said jacket in spaced relation thereto to afford an annular pre-heating chamber, a pair of pre-heating nozzles extending through the respective caps into opposite end portions of said chamber, a row of longitudinally spaced flame throwing nozzles provided on said conduit and extending radially through said chamber to project outwardly from said jacket, and means for delivering fuel under pressure to said conduit and to said pre-heating nozzles.
